FEELER MECHANISM FOR LOOMS

Application filed May 14, 1929. Serial No. 362,916.

This invention relates to feeler mechanisms for looms and more particularly to feeler mechanisms of the side slipping type wherein the operative condition of the loom is changed 5 when the feeler partakes of its side slipping movement.

In one form of side slipping feeler mechanism, movement of the feeler in a direction longitudinally of the shuttle is effected by 10 the forward push upon the feeler when the filling is substantially exhausted on a detecting beat, and, in another form, means are provided to act upon the feeler to impart its side slipping movement independent of front- 15 ward pressure upon the feeler.

In feeler mechanisms of the second form of side slipping feelers, it is desirable that the feeler shall not be subjected to the action of the side slipping moving means until after the 20 feeler has properly engaged the filling, that it may be held from side slipping movement when a working supply is present in the shuttle on a detecting beat, and thereafter, during the frontward movement of the feeler, that 25 the means which imparts to the feeler its side slipping tendency shall act upon the feeler with a substantially uniform force.

One of the objects of the present invention is to provide a feeler mechanism of the side 30 slipping type wherein the means for effecting side slipping movement of the feeler will come into action only after the feeler has been moved frontwardly a predetermined amount and thereafter act with a substantially 35 constant force tending to impart side slipping movement to the feeler.

Another object of the present invention is to provide a feeler mechanism of the type indicated, which shall be simple in construction, light and effective in operation and sensitive both to the presence and absence of filling.

The invention and novel features thereof will best be made clear from the following description and the accompanying drawings of one good form thereof.

In the drawings:

Fig. 1 is a perspective view of portions of a 45 loom at the detecting side, containing the

present invention, and having parts broken away;

Fig. 2 is a plan view showing the relation of parts comprising the invention when a working supply of filling is present in the 55 shuttle on a detecting beat;

Fig. 3 is a similar view showing the relation of parts when the feeler detects substantial exhaustion of filling; and

Fig. 4 is a detail plan view showing the relation of parts when the feeler is in its backward feeling position.

The feeler mechanism in the present instance of the invention is shown as associated with means for initiating filling replenishment when the filling in the shuttle is substantially exhausted on a detecting beat, but the details of the filling replenishing mechanism are not shown because they form no essential part of the present invention and are now well understood in the art.

Extending from the loom frame is the shipper stand 1 having a laterally projecting arm 2 for the support of a bracket 3 which may be secured to the arm 2 in adjusted position by a 75 bolt 4 which passes through an elongated slot 5 in the arm 2.

The feeler stand 6 is adjustably secured to the bracket 3 by means of a bolt 7, passing through a slot 8 in the feeler stand. The 80 feeler stand is shown as formed of light sheet metal and provided with an upturned flange 9 at its rear portion, which is provided with a slot 10, and at the front of the feeler stand is an upturned flange 11 having an opening 85 12. The feeler 13 extends through the rear bearing 10 and front bearing 12 and at its front portion is the laterally turned arm 14 which serves to limit the rearward movement of the feeler to feeling position.

The sensitiveness of a feeler mechanism of the side slipping type depends to a large extent upon the light sensitive character of the feeler itself, and in accordance with the present invention the feeler 13 is formed of wire 95 the longitudinal axis of which is substantially at right angles to the lay movement, with the result that no tendency to side slip is imparted to the feeler by a frontward pressure of a surface on the lay.

The feeler 13 has the projection or bend 15 between the front and rear bearing of the feeler stand, and connected to the projection or bend 15 is a pull spring 16, the rear end portion 17 of which is secured to the rear portion of the feeler stand at a point lateral with reference to the longitudinal axis of the feeler, so that the spring 16 acts in a rearward inclined direction to impart to the feeler its movement to feeling position laterally in the slot 10 in the rear feeler bearing.

The lay 18, only a portion of which is shown, is provided with the usual shuttle box 19 for the reception of the shuttle 20 in which 15 is mounted the filling carrier or bobbin 21 on which the filling is wound, and the front wall of the shuttle is provided with an elongated slot 22 which registers with a similar elongated slot in the front wall of the shuttle box, as usual, so that on each detecting beat the feeler may enter the shuttle and contact with the filling.

From the construction thus far described it will be apparent that the feeler will be 25 moved frontwardly on each detecting beat and have no tendency to side slipping movement and will be returned to its feeling position by the pull spring 16 acting in an inclined and rearward direction upon the feeler.

30 Pivotaly mounted on the feeler stand at the front portion thereof is the feeler displacer, comprising an arm 23 which extends in a laterally inclined frontward direction from the pivotal support or pin 24, so that 35 the front portion of the arm 23 extends across the front end of the feeler out of contact therewith, as more clearly indicated in Fig. 4.

The arm 23 is held in its normal position, as indicated in Fig. 4, by a spring 25, one end 40 of which is connected at 26 to the feeler stand and the other end of which is connected to an arm 27 associated with the inclined arm 23, and a stop 28 which may be formed by the end of the front bearing flange 12 limits the 45 movement of the inclined arm 23 in its operative position under the stress of the spring 25.

The feeler displacer is herein shown as formed of a single piece of material having 50 a pivot embracing portion 29 from which the inclined arm 23 extends frontwardly across the path of feeler movement, and the arm 27 extends in an opposite direction, as indicated in Fig. 1.

55 The feeler stand 6 is provided with a guide 30 through which extends a transmitter 31, the end 32 of which rests against the side of the feeler, with the result that should the feeler side slip, the transmitter 31 will be 60 moved longitudinally and act through a train of mechanism to initiate filling replenishment.

As hereinbefore indicated, the inclined arm 23 extends across the line of feeler movement frontward of the front bearing 12 and

is slightly spaced from the end of the feeler, as indicated at 33, Fig. 4, the construction being such that as the feeler is moved frontwardly by engagement with the filling in the shuttle the single teeth 34 of the feeler will sink into the filling owing to the pull stress of the spring 16, before the front end of the feeler contacts with the feeler displacer, thereby insuring that prior to lateral stress being exerted upon the feeler the filling 70 feeler end will have firmly engaged the filling slot 10 in the rear feeler bearing.

75 As the feeler is moved further frontward on a detecting beat, the front end portion of the feeler will engage the inclined arm 23 of the feeler displacer, which will thereupon act upon the feeler and tend to impart side slipping movement about the front bearing 12 as a fulcrum. The leverage arm frontward of the bearing or fulcrum will remain substantially constant, as indicated at a, Figs. 2 and 3, so that the side slipping tendency of the feeler will remain substantially constant once the front end of the feeler has engaged the inclined arm 23 of the feeler displacer.

80 From the construction described it will be obvious that as the feeler is moved frontwardly by engagement with the working supply of filling, the spring 16 will be elongated and its direction of pull will pass nearer and nearer through the front bearing 12 or fulcrum about which the feeler tends 85 to swing under the constant action of the feeler displacer. When the feeler detects a substantial exhaustion of filling in the shuttle, however, and side slips, the line of spring pull of the spring 16 will move to the right 90 relative to the fulcrum or front bearing 12, thus exerting a tendency in opposition to the side slipping movement of the feeler, but since the oncoming substantially exhausted filling carrier is acting with a frontward 95 push against the tip end of the feeler, now inclined, as indicated in Fig. 3, the two 100 forces, that of the changing direction of pull of the spring 16, and the frontward push of the oncoming bobbin, will substantially 105 neutralize each other, so that the tendency 110 of side slipping movement of the feeler under the action of the feeler displacer will remain 115 substantially constant.

120 The invention provides a simple and effective means to first insure the holding engagement of the feeler with the filling, and second, to exert upon the feeler a tendency to side slip which remains substantially constant under the substantially constant leverage of the feeler displacer upon the front end of the feeler, to insure sensitiveness of feeler action in detecting the presence or substantial exhaustion of filling.

What is claimed is:

1. In a feeler mechanism for looms, the combination of a feeler stand having rear and front bearings, a side slipping feeler extending through both of said bearings, an arm extending laterally from the feeler between the rear and front feeler stand bearings, an inclined pull spring secured at its front end to the laterally extending feeler arm and at its rear end to the rear of the feeler stand, a feeler displacer mounted at the front of the feeler stand and acting upon the feeler forward of the front bearing of the feeler stand to effect side slipping movement of the feeler about the front bearing when the filling is substantially exhausted on a detecting beat, and a transmitter resting against the feeler between the front and rear feeler stand bearings.

2. In a feeler mechanism for looms, the combination of a feeler stand having rear and front bearings, a side slipping feeler extending through both of said bearings, an arm extending laterally from the feeler between the rear and front feeler stand bearings, an inclined pull spring secured at its front end to the laterally extending feeler arm and at its rear end to the rear of the feeler stand, a feeler displacer constituted as a lever pivotally mounted at the front of the feeler stand and acting upon the feeler forward of the front bearing of the feeler stand to effect side slipping movement of the feeler about the front bearing when the filling is substantially exhausted on a detecting beat, and a transmitter resting against the feeler between the front and rear feeler stand bearings.

3. In a feeler mechanism for looms, the combination of a feeler stand having an upwardly projecting flange at the front thereof, a side slipping feeler extending forwardly through said flange, a pull spring connected to the feeler and to the rear of the feeler stand, a feeler displacer pivotally supported at the front of the feeler stand and having an arm extending into the path of the feeler for engagement with the feeler after it has been moved forwardly to a predetermined extent and thereupon acting upon the feeler forwardly of the flange to effect side slipping movement of the feeler when the filling is substantially exhausted on a detecting beat.

4. In a feeler mechanism for looms, the combination of a feeler stand having an upwardly projecting flange at the front thereof, a side slipping feeler extending forwardly through said flange, a pull spring connected to the feeler and to the rear of the feeler stand, a feeler displacer pivotally supported at the front of the feeler stand and having an arm extending into the path of the feeler for engagement with the feeler after it has been moved forwardly to a pre-

determined extent and thereupon acting upon the feeler forwardly of the flange to effect side slipping movement of the feeler when the filling is substantially exhausted on a detecting beat, and a spring connected to the feeler displacer for yieldingly holding it in operative position.

5. In a feeler mechanism for looms, the combination of a feeler stand, a feeler mounted on the stand for side slipping movement, a fixed bearing for the feeler at the front of the feeler stand, a feeler displacer comprising an arm pivotally mounted on the feeler stand and extending in a laterally inclined direction across the front end of the feeler and out of contact therewith until the feeler is moved forwardly a predetermined amount, and a spring for yieldingly holding the arm in operative position to effect side slipping movement of the feeler about the fixed bearing as a fulcrum when the filling is substantially exhausted on a detecting beat.

6. In a feeler mechanism for looms, the combination of a feeler stand, a feeler mounted on the feeler stand for side slipping movement, a pull spring normally acting in an inclined rearward direction upon the feeler to move it into feeling position, a fixed bearing at the front of the stand through which the front end portion of the feeler extends, a feeler displacer comprising an arm pivotally mounted at the front of the feeler stand and extending in a laterally inclined direction into the path of the feeler movement and normally out of contact with the feeler until the feeler is moved forwardly a predetermined amount, and a spring connected to said arm for yieldingly holding it in operative position to effect side slipping movement of the feeler about the front bearing as a fulcrum when the filling is substantially exhausted on a detecting beat.

7. In a feeler mechanism for looms, the combination of a feeler stand having front and rear bearings, a light wire side slipping feeler mounted in said bearings, a pull spring connected to the feeler and to the rear of the feeler stand and acting in an inclined direction upon the feeler, a feeler displacer constituted as an arm pivotally mounted at the front of the feeler stand and extending in a laterally inclined direction into the path of feeler movement in front of the front bearing, a spring connected to the arm for yieldingly holding it in operative position, and a stop for limiting the movement of the arm under the stress of the spring that the front end of the feeler may engage the arm at a predetermined distance forward of the front bearing as the feeler is moved forwardly on a detecting beat.

In testimony whereof, I have signed my name to this specification.

JESSE W. SIMPSON.
